(57) **CLAIM**

The ornamental design for a chisel machine, as shown and described.

DESCRIPTION

FIG. 1 is a perspective view of a chisel machine design showing our new design.

FIG. 2 is a front view of a chisel machine.

FIG. 3 is a rear view of a chisel machine.

FIG. 4 is a left side view of a chisel machine.

FIG. 5 is a right side view of a chisel machine.

FIG. 6 is a top view of a chisel machine.

FIG. 7 is a bottom view of a chisel machine; and,

FIG. 8 is a bottom side perspective view of a chisel machine.

1 Claim, 8 Drawing Sheets
